UNITED STATES PATENT OFFICE.

JOHN L. INMAN, OF PUTNAM, CONNECTICUT.

BAND AND CORD TWISTING MACHINE.

SPECIFICATION forming part of Letters Patent No. 426,383, dated April 22, 1890.

Application filed February 15, 1889, Serial No. 300,070. (No model.)

To all whom it may concern:

Be it known that I, JOHN L. INMAN, a citizen of the United States, residing at Putnam, in the county of Windham, State of Connecticut, have invented certain new and useful Improvements in Band and Cord Twisting Machines, of which the following is a specification, reference being had therein to the accompanying drawings.

10 The object of my invention is to provide a machine whereby all the steps in the twisting and doubling of cord, from the supply of the parallel strands to the removal from the twisting-jaws, are performed automatically 15 by the same machine, and without the intervention of intelligent guidance during the operation.

My machine is more particularly designed 20 for making loop-bands for rope-pulleys; but of course I do not limit myself to this use of the machine, as it is evident that any form of cord can be made by it without the change even of details.

In the drawings, Figure 1 is a perspective 25 of the working end of my machine, showing the tracks broken near the forward end of the same. Fig. 2 is a perspective of the holding end of my machine, showing a portion of the other ends of the tracks. Fig. 3 is a side 30 view of a portion of my machine with the feed-funnel, the front counter-shaft and the rear shaft and removing-shaft not shown. Fig. 4 is a top view or plan of a portion of my machine with the cam-shaft and feed-funnel 35 removed. Fig. 5 is a rear view of a portion of my machine, illustrating the reversing-gear attached to the driving-pulley of my holding mechanism. Fig. 6 is a detail of the 40 gearing used for transmitting the power of the rear shaft to the driving-pulley and to the cam-shaft, said figure showing said details from the front, with all mechanism forward of said gear removed. Fig. 7 is a detail of the beveled brake, seen from the rear, and 45 showing its connection with the cam that operates it on the cam-shaft. Fig. 8 is a side view of my machine from the opposite side from that shown in Fig. 3, showing the rear shaft, together with the shifting mechanism 50 and the rear notched gear and lever. Fig. 9 is a front view of a portion of my machine,

only showing the revolving gear and the removing device, together with the feed-funnel and its reversing-gear. Fig. 10 is a side view from the direction of the removing-shaft of 55 the twisting-jaws and the position of the feed-funnel with regard to said jaws when in operation. Fig. 11 is a top view of the forward portion of the power-shaft, showing the details of the twisting and doubling mechanism in central horizontal section. Fig. 12 is a detail of the circular cam and its operating mechanism as seen from the forward part of the machine. Fig. 13 is a detail of the clutch between the independent sections of the rear 65 shaft, showing the pulleys in section. Fig. 14 is a top view of the removing-fingers at the moment when they close upon the completed cord. Fig. 15 shows a detail of the reversing-arm and of the cam operating it. 70 Fig. 16 shows the detail of the notched gear on the power-shaft, the lever controlling the same, and the cam operating said lever. Fig. 17 is a side elevation of my preferred 75 form of clutch between the two rear shafts.

The power whereby my machine is operated is applied thereto by means of belts running upon two shafts A and B, termed, respectively, the "rear shaft" and the "power-shaft." Each of these shafts is provided with 80 two pulleys—the loose pulley B¹ and the tight pulley B² upon the power-shaft and the constant pulley A' on the constant driving-shaft or constantly-moving section of the rear shaft and the intermittent pulley A² on 85 the twisting-shaft or intermittently-moving section of said rear shaft. These two sections of the rear shaft come together between the two pulleys, as shown in Fig. 13, where they are provided with clutches, which are 90 operated by means hereinafter described. The intermittent section is the forward one, and, as shown in Fig. 4, is provided with the following parts:

Just forward of the intermittent pulley is 95 the gear A³. This is a smooth wheel having a notch in its periphery, which is intended for co-operation with a lever, as hereinafter described. Forward of this gear is the smooth friction-wheel A⁴, which is intended for co- 100 operation with the beveled brake B³. On the end of the shaft and beyond the bearing, as

shown in Fig. 4, is the gear-wheel A⁵, employed in the operation of the outside and inside gear on the end of the power-shaft.

The constant section of the shaft is situated back of the interposed clutches and bears the following parts: Next to the pulley A' is the spur-gear A⁶, for use with the intermediate gear, hereinafter described. Just back of this gear is the worm A⁷, the rear side of which abuts against the back bearing of the rear shaft, as shown, Fig. 4. This worm is employed for the purpose of running the "transmitting-shaft," so called because it carries the power of the rear shaft to the cam-shaft C, to the secondary cam-shaft F, and to the vertical shaft G. This transmitting-shaft is shown best in Figs. 5 and 6 at H. In these two figures this shaft is seen from opposite sides, and in Fig. 6 the end bevel-gear H' is left out. This bevel-gear is on the inner end of the shaft H and is geared with the bevel-gear E' on the end of the shaft E, which operates the removing parts of the machine. Next to this gear comes the worm-wheel H², which gears with the worm A⁷, and through which the power is imparted to the transmitting-shaft. Between the two middle bearings, as shown in Fig. 6, comes the transmitting-worm H³, and beyond the outer bearing, as shown in Fig. 5, is placed the bevel H⁴, which operates the carrying-wheels, as hereinafter described. Meshing with the worm H³ is the worm-wheel F' back of the frame of the machine and mounted rigidly upon the secondary worm-shaft F. Within the frame and mounted upon the front end of said shaft F is the spur-wheel H⁵, which gears with the corresponding spur-wheel on the end of the cam-shaft C, as shown at C'. Upon this cam-shaft C are mounted eight cams, as follows: C², the cam that operates the lever going to the notched gear on the front shaft; C³, this and cam C⁴ are alike, save that they are differently placed with regard to the shaft, and they are both used for the operation of belt-shifters, as hereinafter described; C⁵, the cam that operates the lever to the notched gear on the rear shaft; C⁶, the cam operating the beveled brake, as shown in Fig. 3; C⁷, the cam operating the pin and lever for raising the rack on the feed-funnel carriage, as hereinafter described; C⁸, the cam operating the circular cam on the power-shaft for closing the holding-jaws, and C⁹ the cam operating the cutter or shears, as shown.

B is called the "power-shaft" because, although the main power is not applied directly to it, the power which is applied thereto is that which accomplishes the main function of the machine—that is to say, the doubling of the cord. As seen clearly in Fig. 4, this shaft is operated independently of the other shafts, save for the interposition occasionally of the intermediate gear, as herein-after described. The parts operated by this shaft and rigidly mounted thereon are as follows: Farthest to the rear is the crown-

gear B⁴, which has a portion of its teeth cut away, which is used in connection with the intermediate gear heretofore alluded to. B⁵ 70 is a notched gear coming just forward of said crown-wheel and used, as before mentioned, in connection with the cam C² and a lever operated thereby. Farther forward are placed the pulleys B' and B², and then the beveled 75 brake B³, employed in connection with the cam C⁶ and the friction-wheel A⁴ on the rear shaft, for a purpose hereinafter described. On the end of this shaft (see Fig. 11) is the revolving head B⁷, and between this revolving head and the beveled brake is placed the circular cam B⁶, which turns loosely on the shaft B, for the purpose hereinafter described. 80

Two holes are made in the revolving head, which holes are placed diametrically opposite 85 one another, and through which are inserted the spindle-cases B⁸. These cases are hollow, as shown, and are provided with a narrow waist portion, which projects through the holes in the revolving head, and with widened 90 parts acting as flanges on the inner and outer faces of said head. On the front faces of these cases are placed the flanges B⁹, which may be made either integral with or separate from the rest of the spindle-cases. Through 95 these spindle-cases and through the slots B¹⁰ in the circular cam B⁶ project the spindles B¹¹, and around said spindles are wound the spiral springs B¹², Fig. 11. These springs tend to keep the spindles forced outward, as shown 100 in the case of the upper spindle in Fig. 11.

The enlarged portion B¹⁶ of the spindle-cases is a gear, and is provided with a square perforation, through which extends a square portion of the spindles. Outside of this revolving head and its auxiliary devices is placed the outside and inside gear J. (See Fig. 9.) The outside teeth of this gear mesh with the wheel A⁵ and the inside teeth with the gears B¹⁶. On the outer end of each spindle is pivoted a pair of jaws B¹³, hinged by means of links B¹⁴ to the flange B⁹ and provided with a square shank fitting into the square perforation in the gear B¹⁶ when the spindle is drawn back, as shown in the lower 110 spindle in Fig. 11. The rear end of each spindle, after passing through the circular cam, through the curved slots B¹⁰, as shown in Fig. 12, is provided with a beveled head B¹⁷, a collar B¹⁸, and a nut B¹⁹. The beveled 120 head has an undercut bevel and straddles the spindle as it emerges through the slot B¹⁰.

Fig. 12 shows the circular cam from the front, and in dotted lines therein are shown the curved cams B²⁰ and B²¹. One of these is 125 longer than the other, as shown, and both extend along either side of the curved slots B¹⁰. As indicated in dotted lines, these cam-slides have beveled ends which correspond to the undercut bevels in the shoes on the ends of the spindles, and when the cam is turned in the direction indicated by the arrow in Fig. 12 these slides are projected under the shoes 130 of each spindle successively, thus forcing the

undercut bevel to ride on the beveled face of the slide and raising the shoes and spindle into the position shown in the lower spindle in Fig. 11. The unequal length of the slides, 5 as shown in Fig. 12, is for a purpose about to be explained.

Reverting to Figs. 3 and 4, we see that the vertical shaft G takes its movement from the bevel-gear H⁴ by means of the bevel-gear G'. 10 By means of the bevel-gears G² and D' this motion is transmitted to the front counter-shaft D. Near the forward end of this counter-shaft is fixed the wheel D², on which is mounted the side projecting pin D^{8x}. In Fig. 15 8 may be seen the horizontal pin K'. On this pin is mounted the arm K, Fig. 12, provided with the pivoted spring-pressed arm K² and the rigid downwardly-extending arm K³. This arm K overlies the cam C⁸ on the cam-shaft 20 C and is provided with a pin K⁴, intended for occasional engagement with the pins C¹⁰ and C¹¹ on the surface of the cam C⁸. The spring-pressed arm K² is pivoted, as shown, to the 25 end of the arm K. Motion in one direction is prevented by means of the stop K⁵, and in the other direction such motion can only take place against the action of the spring K⁶. This spring is for the purpose of keeping the arm K² up against the edge of the circular 30 cam B⁶ and to allow of the sliding of the said arm K² over the notches shown on the edge of said circular cam. The operation of these various parts will then be as follows: As the cam C⁸ revolves in the direction 35 shown by the arrow it catches on the tooth K⁴ on the arm K and raises said arm until the foot of the arm K³ is thrust out into the path of the pin D^{8x} on the revolving wheel D² on the shaft D. This wheel revolves in the direction of the arrow and turns with greater 40 velocity than does the cam C⁸. As the pin comes up under the arm K³ the whole piece K is thrust upward, forcing the arm K² into the notch B²² in such a manner as to cause 45 the circular cam B⁶ to turn through a portion of a revolution in the direction of the arrow. Hitherto the end of the sliding cam B²⁰ had been just touching the edge of the shoe on one of the spindles B¹¹—namely, the lower 50 one. (Shown in Fig. 11.) This movement, however, causes the sliding cam to raise the shoe on the end of said spindle, as heretofore explained, and to bring said spindle into the position shown in the case of the lower spindle 55 in Fig. 11. The spindle being thus raised or pulled backward drags the jaws B¹³ after it and draws the square shank of said spindle-jaws after it into the aperture in the gear B¹⁶. The links B¹⁴ also conspire to prepare the 60 jaws for entrance into said aperture by their squeezing action and the shortening of the distance between their ends incident to their pivotal attachment to the flanges and the inward movement of the jaws. This dragging 65 of the jaws into the square aperture causes them to close tightly and suddenly, for a purpose hereinafter described. This jaw having

been closed, there is an appreciable halt, and then the slowly-moving cam C⁸ again catches the pin K⁴, this time by means of the pin or tooth C¹¹, and the above-described operation is repeated. This time the shorter sliding cam B²¹ is in turn thrust under the shoe on the other spindle, and the other pair of jaws is shut with a snap. Of course it must be 75 understood that the arm K² is in contact with the edge of the circular cam only when the arm K is raised by the tooth on the cam C⁸.

The holding portion of my machine consists of a carriage a, borne on wheels b, running on the tracks 1 and 2, which are placed under the base of the working portion and extend to any length, according to the length of cord to be wound at once, and on said carriage is borne a standard c, carrying a hook d, pivoted to said standard at e. An endless cord passes around the carrying-wheels 3 and 4 and is attached at one point to the bottom of the carriage a. By the running of this cord over these carrying-wheels one way or 80 the other the carriage is brought toward or carried away from the working part, as described farther on. This movement of the cord and corresponding revolution of the carrying-wheels in one direction or the other is 85 accomplished as follows: The vertical shaft G receives its motion from the transmitting-shaft by means of the gears H⁴ and G'. At the bottom of the shaft G is fixed the wheel G³, turning in the direction indicated by the 90 arrow, and meshing with said gear-wheel G³ are the two bevel-gears G⁴ and G⁵, turning necessarily in opposite directions. These bevel-gears turn loosely upon the shaft of the carrying-wheel 3. A clutch provided with 95 teeth G⁶ is arranged to slide on said shaft of the carrying-wheel and is kept from turning on said shaft by a feather or other analogous means.

The secondary cam-shaft F, Figs. 3 and 4, 100 bears at its outer end two cams F² and F³. The latter is for a purpose hereinafter described, and the former is employed in operating the reversing-shaft, as follows: The cam F² has two flanges in the planes of its faces, 105 said flanges having projections F⁴ and F⁵, turned inward and so beveled with regard to the direction of the revolution of said cam (shown by the arrow in Fig. 4) as to cause the backward and forward movement of the 110 lever L', fixed by screws or other means to the reversing-shaft L. This cam F² turns, of course, very slowly by means of the action of the worm H³ on the worm-wheel F'. As seen by comparing Figs. 4 and 8, there are two sets 115 of these oppositely-arranged teeth for the purpose of the revolving of the reversing-shaft, one set acting to turn the lever so as to run the carrying-wheels in a positive direction and drive the carriage away from the 120 working portion of the machine, and then setting it back into a neutral position as soon as said carriage has reached the end of the 125 track, and the other set of teeth acting to

move the reversing-shaft all the way in the contrary direction and bring the carriage back to the working portion, bringing the lever into a neutral position again as soon as the carriage reaches the near end of the track again.

The reversing-shaft is borne in the bearings 8 and 9, Fig. 5, and is adapted to turn in said bearings, said turning being accomplished by means of the shifting of the lever L' by means of the beveled teeth on the inside of the flanges of the cam F². The clutch G⁶ is borne on the end of a lever similar to the lever L', but set at the end of the shaft L, as shown at L². According as the shaft is turned in one direction or the other, said clutch is thrown into gear with one or the other of the gears G⁴ and G⁵, which are turning in opposite directions, and, since the clutch can only slide and cannot turn on the shaft of the carrying-wheel, said shaft and said wheel is carried in the direction required, according to which gear-wheel it is brought into gear with. Thus the movement of the carriage a is controlled by the slowly-revolving cam F², and said cam is placed in such a position upon its shaft as to make the proper movements of said carriage occur at the proper time. About midway between the ends of the reversing-shaft is fixed the arm or lever L³, the end of which is attached to the end of the track 1, as shown in Fig. 5, and said track 1 is arranged to slide within its bearings by the action of this arm L³ at the proper time, and for a purpose hereinafter described.

Returning to Fig. 2, it will be seen that the end of the hook d is embraced by a turned end of the top of the standard c, which I call a "scraper," as it is used for the purpose of scraping against the outer edge of said hook for the purpose of removing the cord at the proper time, as will be shown. The depending end d' of the hook is held toward the vertical position by means of the spring d², in order to counterbalance the weight of the horizontal hook-arm proper and to allow of the springing of this arm past the trip 10. The tip of the hook projects, as shown, up past the scraper, and is intended for the holding of the middle of the cord in the process of twisting and doubling. On the inner side of the standard c is fixed a pin or other support g, over which extends and upon which weighs the brake 11, which is preferably a metal bar pivoted to the track 1 or to a sleeve upon it, as at 12. This brake is for the purpose of retaining the carriage in its proper position during the operation of doubling, when by the shortening of the cord incident to this operation said carriage would tend to be dragged unduly near the working portion of the machine, and thus cause a slackening of the cord, which would end in the tangling of the cord and destruction of the work. Any form of brake would answer in this connection; but I prefer this form, as it is very sim-

ple and co-operates naturally with the track 1 for its undoing. It may be as well to state here, in anticipation of the description of the mode of operation of my machine, that just as the operation of doubling is completed the carriage is found near the end of the lever 11, having been carried there by the gradual shortening of the cord incident to its doubling.

Fig. 16 shows a detail of the cam C² and the notched gear B⁵ and their mode of co-operation by means of the bell-lever M. Said bell-lever is pivoted at the point M³ and is composed of two arms—M², horizontal, and M', vertical. The arm M² rests at one end upon the cam C² and is kept in contact therewith by the action of a spring M⁴, attached to the frame of the machine. The other arm M' is provided with a projection which enters a corresponding notch B^{5x} in the periphery of the gear B⁵ on the power-shaft to which it is fixed. As shown in Fig. 16, said projection is on the point of being removed from the notch on the gear B⁵, and it is evident that it only remains therein during the contact with the end of the arm M² of that portion of the periphery of the cam C² which is included between the dropping-point C^{2x} and the point shown in contact on the figure; hence during the greater part of the time said projection on the arm M' is out of the notch B^{5x}. During this time the power-shaft is revolving.

Fig. 15 shows a detail of the shifter for the front belt, which is managed by means of a cam C⁴, turning in the direction shown in the drawings, this figure being seen from the direction of the front of the machine. The arm N is pivoted to the frame of the machine at N', and has a pin, which is shown at N², and is made to continually bear against the side of the cam C⁴ by means of a spring or otherwise, according to the fancy of the builder, as this is a matter of mere mechanical skill. The bearing of thinner or thicker portions of the cam against this pin throws the arm to one side or the other, and the top of said arm is made in the same form as the shifter on the back shaft, as shown at O' in Fig. 8. This looped portion of the arm embraces the strap or belt that runs the power-shaft and causes it to follow its movement onto one pulley or the other.

In the case of the shifter on the rear shaft the cam C³, that operates it is of the same character as that which operates the shifter on the front or power shaft; but there are details necessarily added to this shifter, as follows: The shifting-arm O is pivoted to the frame at O², near which point of pivoting there branches out from the main standard a supplementary arm, to which is pivoted a two-armed bell-crank O³ O⁵, as shown in Fig. 8. A pin O⁴ is borne on the arm O, and is so placed as to intersect the path of the end of the arm O⁵ of the bell-crank. Now, it will be seen that when the belt is shifted by the arm O from the constant pul-

ley to the intermittent pulley the pin O^4 will strike against the end of the arm O^3 and turn the bell-crank, so as to push the arm O^5 against the disk P , Fig. 13, and as this disk is made so as to slide upon the shaft A at will the disk acts by means of the pins P' to thrust the clutch P^2 into gear with the clutch P^3 on the end of the constantly-moving section of the shaft A . Now, as the belt is constantly moving so as to revolve this clutch in the direction indicated by the arrow, the square ends of the teeth on the clutch P^2 will act against the square ends of those on the other clutch, and consequently the two pulleys A' and A^2 will become practically one, and the shifting of the belt will cause no interruption of the motion of the constantly-moving section of the shaft A . When, on the contrary, the belt is shifted onto the pulley A' , the power continuing to act in the direction of the arrow, the beveled sides of the teeth on the clutch P^3 will act on the correspondingly-beveled sides of the teeth on the clutch P^2 , and the consequence will be the automatic throwing apart of the clutches and the consequent replacing of the disk in position for the renewed action just described. All these movements then are regulated by the cam C^3 , which directs the action of the shifter on the rear shaft, and it is the setting of this cam that settles the accuracy and timeliness of the movement.

Figs. 1, 3, 9, and 10 show the details of the feed mechanism whereby the rovings or parallel strands are placed in position automatically by the action of the carrying-wheel and appropriate cams and gears. The standard Q of the feed-carriage supports a horizontal funnel Q' , which is set in the plane of the jaws when in their normal position, and so near to them as to pass between them when moved in a horizontal line before them as guided by the tracks between which the carriage moves. The bottom of this carriage is contained between the sides of the casing 13, which is grooved, as shown in Fig. 3, and which acts to guide said carriage in its aforesaid movement before the jaws. The funnel Q' is hollow and is of the proper diameter to allow of the passage of the rovings or strands with the proper amount of friction, said rovings projecting beyond the end of the funnel a distance of the width of the jaws B^3 . To the bottom of the carriage is pivoted a rack, as shown in Fig. 9 at Q^3 . This rack is normally in a drooping position, and is only held in an approximately horizontal position by the bottom of the casing 13. When the carriage is in its forward position, as shown in Fig. 9, this drooping of the rack is particularly marked, as there is less of it resting on the bottom of the guide.

Underneath the frame of the machine is a lever R , pivoted at R^2 and bearing at one end a pin R' , which passes up through a sleeve 14 on the frame-work and bearing against the periphery of a cam C^7 on the

cam-shaft. At the other end of this lever is a pin which passes up through the bottom of the guideway and bears upon the under surface of the rack. By the revolution of the cam C^7 with the cam-shaft the pin R' is depressed at intervals and the pin R^3 correspondingly raised until the rack is forced up thereby into gear with the broken gear D^3 (shown in Fig. 9) on the end of the counter-shaft D . This action of the cam is timed to take place just as the teeth on the broken gear come into the position shown in the figure, and thus the carriage is carried back, as will be further explained.

Q^4 is a roller on which the drooping end of the rack is allowed to rest when out of gear with the broken gear, as shown in dotted lines in Fig. 9. When the carriage is in the position shown in Fig. 1, it is held in place against the action of the weight 16 by means of the latch 15, which is adapted to slide up onto the pin g of the holding-carriage. When this latch is so raised by the pin g , the weight 16 is allowed to come into play through the cord 22 over the pulley 16^2 , and the carriage and funnel are made to slide down the guide into the position shown in Fig. 9. When in due time the pin R^3 raises the rack into gear with the wheel D^3 , the carriage is carried back and the number of teeth upon said wheel D^3 is calculated to just carry it back into the power of the latch 15, at which time the smooth part of the wheel comes over the rack and there is no further action.

As seen in Fig. 11, the beveled brake B^3 is lined with leather and rides loosely upon the shaft B . It is so formed as to fit the outside beveled conical surface of the circular cam and to act as a brake upon its rotation in case of need. In Fig. 3, as also in Fig. 7, is shown the friction-shaft S . At the bottom of this shaft is a spiral spring or other device for the purpose of turning the shaft in such a direction as to press the arm S^2 against the beveled brake and close it up against the top of the circular cam. This spring is shown at S' , Fig. 3. This action of the spring is, however, prevented by the bearing of an arm S^3 , fixed to the shaft S , against the cam C^6 . At the proper moment this cam, which is revolving in the direction indicated by the arrow, allows the arm S^2 to drop into the notch C^6 , and thus permits the arm S^2 to act and throw the beveled brake against the top of the circular cam by the action of the spring S' . When this action has been sufficiently prolonged, the inclined side of the cam comes into play and the arm S^3 is pushed slowly out of the notch in the cam and the beveled brake is cleared of the cam. A spring S^4 , interposed between the arm S^2 and a projection S^6 on the beveled brake, tends to turn said beveled brake against the direction of the arrow. A pin S^5 is placed on the back of the beveled brake in such a position as to properly limit this tendency of the spring S^4 , and the two keep the beak S^7 normally out of contact.

with the friction-wheel A⁴. This beak is an integral part of the beveled brake, and is coated, preferably, with leather on its under side in order to oppose a considerable friction to the wheel A⁴.

Turning to Fig. 5, we see a back view of the machine and a detail of the action of the back cam F³. This cam turns with the secondary shaft, on which it is mounted, in the direction of the arrow, and upon it rides a hooked arm T'. Upon a pivot T⁵, extending through a portion of the back part of the frame, is fixed the stud-plate T, having two bearings upon it for the sets of gears shown in the figure. These gears are the spur-wheel T⁴, destined for gearing with the spur-wheel A⁶, Figs. 4, 5, and 6, the spur-wheel T², gearing constantly with the spur-wheel T⁴, and the pinion T³ on the same bearing with the spur-wheel T² and meshing with the spur-wheel B⁴ on the power-shaft. On the other end of the pivot T⁵ is the arm T', which is fixed thereto, and which by means of the constant bearing of its end upon the cam F³ keeps the stud-plate swung up into such a position as to hold the gears it bears out of mesh with the spur-wheels B⁴ and A⁶. This set of wheels on the stud-plate is then called the "intermediate gear," as it is intermediate between the rear shaft, to which constant power is attached, and the power-shaft. Its purpose will be explained farther on. Of course, as the notch is brought around until it comes under the end of the arm T', said end drops into it, and the intermediate gear is allowed to connect the rear shaft and the power-shaft, as specified. At the proper time the inclined face of said notch lifts said arm T' out of said notch and the gear is again free. The shaft E, which is run by means of the bevel-gear E', bears at its other end a small spur-wheel E², which gears with another spur-wheel E³, which runs the remover, as will be explained farther on.

The cam C⁵ operates in all respects in the same manner as the cam C², save that the notched gear with which it is connected is situated on the rear shaft, as shown in Fig. 8 at A³, where also the connecting-lever is shown at C⁵. The purpose of this lever and notched gear is analogous to that of the notched gear and lever on the front shaft, as will be further explained.

The cam C⁶ is shown in small detail on the left of Fig. 3, and is used for operating the cutting mechanism. This consists of two portions U and U², the latter being fixed to the frame of the machine and the former being movable and pivoted at U'. The inner end of the portion U extends within the frame of the machine back of the pivot, and its end rests upon the top of the cam C⁶, against which it is constantly held by means of the spring U⁴ or its equivalent. The inner edge of the portion U and the outer edge of the portion U² are sharpened in order to admit of the cutting of the cord at the proper moment. This operation is brought about by the arrival of

the drop in the cam, as shown in the small side detail referred to, and when this portion of the cam is made to come under the arm U³ of the cutter the spring U⁴ thrusts said arm downward upon the cam and the cutting action is complete, since the cutters are thus brought into contact.

The operation of the machine will then be as follows: Taking the machine at the moment when a cord has just been completed, the belt on the rear shaft is on the constant pulley and the shafts F, G, H, and D are in motion, the cam F² being on the point of thrusting the lever L' toward the right in Fig. 4 and bringing the clutch G⁶, Fig. 5, into gear with the bevel-gear G⁴. The jaws, funnel, &c., are in the position shown in Fig. 1. At this moment the projection F⁵ on the cam F², Fig. 4, comes against the lever L' and thrusts it to the right, throwing the clutch G⁶ into gear with the bevel-gear G⁴. As seen by the direction of the arrow on this gear, the carrying-wheel 3 is thus made to revolve in the direction opposite to that of said wheel in the figure, as shown by the arrow on said wheel. This wheel carries the endless cord with it, and the effect of this rotation is to bring the holding mechanism toward the working part of the machine. This brings the hook d³ between the jaws B¹³ and causes the pin g, Fig. 2, to raise the latch 15, Fig. 1. This latch being raised, the funnel-carriage is liberated and the weight 16 brought into operation, thus drawing the funnel forward past and between the two pairs of jaws B¹³, as plainly shown in Figs. 9 and 10. In this position, as shown in dotted lines in Fig. 9, the rack is depressed and out of gear with the wheel D³. At this moment another projection on the cam F² thrusts the lever into a neutral position and the carrying-wheels cease to act on the carriage of the holding mechanism. As the funnel now stands the rovings contained therein project beyond the end of said funnel and stand in a position to be grasped by the right-hand pair of jaws in Fig. 9. At this moment the cam C⁸, Figs. 3 and 12, is brought into such a position that the pin C¹⁰ raises the arm K, and by the action of the pin D³ on the wheel D² the right-hand jaw in Fig. 9 is closed with a snap, and the end of the rovings clipped thereby. At this moment the cam C⁷ is brought into operation and the pin R³ thrusts upward, bringing the rack Q² into gear with the wheel D³ on the end of the shaft D, which by this time has just reached the position shown in Fig. 9. The rotation of this shaft returns the funnel to its position in Fig. 1, the rovings therein being drawn therethrough by the holding of the end thereof by the jaws B¹³. As soon as the teeth on the wheel D³ have all acted and the carriage is brought back into the position shown in Fig. 1 another projection on the cam F² thrusts the lever L' in such a direction as to bring the clutch G⁶ into gear with the bevel G⁵, and the carrying-wheel is made to revolve

in the direction of the arrow thereon and the carriage returns to its position in Fig. 2. As it comes back into this position the pin g enters underneath the brake-lever 11, 5 which has been brought forward for that purpose by the action of the lever L^3 , Fig. 5. Fixed to one of the jaws of the left-hand pair in Fig. 1 and extending through a perforation in the other jaw is a curved pin 17, 10 between which and the intersection of the jaws the funnel was made to pass, as above specified. The effect of this pin is to retain the rovings, that would otherwise extend from the mouth of the funnel to the hook and 15 thence to the right-hand pair of jaws. Thus these rovings are made instead to extend from one pair of jaws to the hook and thence back to the other pair of jaws. No sooner has the holding-carriage reached its position, 20 as shown in Fig. 2, when the cam-pin C^4 on the cam C^8 , Fig. 12, reaches the pin K^4 and the arm K is raised again, with the effect of closing the left-hand pair of jaws on the other end of the rovings which extend therethrough, 25 as above specified. At the next moment the cam C^9 brings the drop-notch under the end of the arm U^3 and the spring U^4 causes the cutting of the rovings between the end of the funnel and the left-hand pair of jaws. 30 Hitherto, as specified, the belt on the rear shaft has been running on the constant pulley; but as soon as this cutting is effected the cam C^3 shifts the belt onto the intermittent pulley, and the clutch between the two pulleys is 35 shot, making the two pulleys practically one, as described above. Thus the action of the cam-shaft is not interrupted. This shifting, however, causes the gear A^5 to revolve, and with it the inside and outside gear on the 40 revolving head B^7 . This inside and outside gear J , being driven from the outside itself, drives the gears B^{16} on the spindles by means of the inside gears, and this with a high velocity. These spindles then, carrying the 45 pairs of jaws, remain thus far in the same horizontal plane; but they revolve upon their own axes, and there is a twisting set up in the two sides of the cord between the holding-hook and the jaws. This hardens the cord in 50 preparation for the doubling process. The direction of this twisting motion can be plainly seen from inspection of Fig. 9, where the arrows show the revolution of all the gears. As will be seen farther on, the twisting motion 55 must be prolonged far beyond the degree of twist necessary in the finally-prepared cord, inasmuch as there is a tendency to undo this twist present during the doubling process. This revolution is, as may be seen, in the 60 same direction in both the spindles. As soon as this twist is completed the cam C^{5X} liberates the lever C^{5X} , and at the same moment the shifter C^3 returns the belt on the rear shaft to the constant pulley. The forward part of 65 the rear shaft now revolves only with its own inertia, and the projection on the end of the lever C^{5X} , resting against the wheel A^3 , Fig. 8,

enters the notch on said wheel and at the proper moment definitely arrests the motion of said rear shaft. This notch is so placed 70 with regard to the gearing of the rear shaft with the gear J that when by its means the rear shaft is stopped the opening lines of each pair of jaws are in the same horizontal plane, the spindles themselves not yet having left 75 said plane. The object of this adjustment of the stoppage of the rear shaft is to insure the opening of the jaws in such a position that the funnel will pass easily between them, the adjustment of said spindles themselves 80 being managed by means of the analogous device B^5 , Fig. 3. The belt on the power-shaft has hitherto been running upon the loose pulley B' , and at this moment the shifter C^4 shifts the belt upon the tight pulley B^3 , 85 thus setting the power-shaft into motion in the direction of the arrow in Fig. 7. This carries the jaws, and with them the ends of the cords, around one another in a vertical plane of revolution in the same direction as 90 the twisting motion of the inside and outside gear. This doubling of the cord from the hook of the holding mechanism causes a shortening of the cord and a consequent slow motion of the carriage toward the working 95 mechanism, which motion is controlled by the action of the brake on the pin g . When this doubling action has been carried on sufficiently, the removing-jaws come into play in the following manner: The wheel E^3 , Fig. 10, 100 operated as described above, runs on a common shaft with the wheel V , Fig. 9, which latter is provided with two series of teeth V' , consisting of five teeth, and V^2 , consisting of three teeth. Just forward of this wheel V is 105 pivoted the shaft V^X , bearing the pinion V^4 and the fixed arm V^5 , Figs. 9 and 14. Pivoted to the arm V^5 a little distance from its point of attachment to the shaft V^X is the arm V^7 , connected with the beak V^8 by the 110 pivot-pin V^6 , Fig. 14. A spiral spring or its equivalent serves to keep the arm V^7 in the position shown in Fig. 9, which is the position preserved during the actions above noted and described. During these operations, 115 however, the wheel V has been constantly revolving in the direction indicated by the arrows in Fig. 9, and just as the doubling action described above is completed the first series of teeth V^2 comes into play against 120 the teeth of the pinion V^4 and raises the arm V^5 into the position shown in Fig. 14, where the arm V^7 is shown as forced down upon the arm V^5 by the agency of the beak V^6 , which is brought into contact with the spring-guard 125 V^3 for this purpose of thus closing the removing-arms. The length of these arms is such as to bring the completed cord between them, as shown in Fig. 14, and while in this position the jaws on the revolving head are opened, 130 as will be further described, and the cord left to the grasp of the arms V^5 V^7 . A moment later the second series of teeth V' comes into play against the teeth of the pinion V^4 , and

the shaft V^x is revolved through such an arc as to sweep the beak V^8 over the whole inner length of the spring V^3 and deposit the cord on hooks or other receiving devices, as may be convenient. The shaft V^x extends the whole length of the machine from the hook to the jaws, and there are two arms besides those shown in Fig. 9 fixed to said shaft, that next the hook of the holder being similar to that just described. The consequence is, that as the cord is raised the tip of the arm d' of the hook, Fig. 2, catches against the trip 10 and the spring d^2 is extended, thus lowering the point of the hook and allowing the cord to be scraped against the scraper and abandoning said cord to the grasp of the arms at this end of said cord.

The opening of the jaws above alluded to, and which is necessary for the removal of the cord, is accomplished as follows: The arms or jaws having grasped the cord and the pinion being between the periods of its engagement with the series of teeth on the removing-wheel, the cam C^6 comes into such a position as to allow S^3 to enter the notch C^{6x} , Fig. 3. This allows the action of the spiral spring S' or its equivalent in thrusting the beveled brake against the surface of the circular cam by means of the bifurcated lever S^2 . By the friction of these two surfaces the beveled brake is thrown over in the direction of the arrow, Fig. 7, and the beak S^7 is projected against the periphery of the friction-wheel A^4 on the rear shaft. The circular cam is thus held practically rigid by the friction of B^3 , and the inertia of the revolving head and the spindles carries them on, throwing the spindles out of the position occupied upon the upper surfaces of the sliding cams on the circular cam and allowing the spiral springs to come into play and throw open the jaws, liberating the cord.

I do not wish to be understood as limiting myself to the means herein specified for operating removing-arms swinging in front of the twisters in a direction at right angles to their length, as I believe swinging arms of this character to be broadly new in the art.

Thus far we have seen the operation of the machine, and all that now remains is to explain the means of bringing it into operative position preparatory to the repetition of this operation.

Of course the inertia of the power-shaft will carry it some little distance against the friction of the bevel B^8 , and the probabilities are, that said shaft will stop its motion in some position incompatible with the coincidence of the jaws with the horizontal plane. In order then to bring them back into this plane, the cam F^3 , Fig. 5, comes around after the stoppage of the power-shaft and brings the drop-notch under the end of the lever T' . This allows the intermediate gear to fall into gear with the crown-wheels A^6 and B^4 , as heretofore explained. Now, as the wheel A^6 is constantly revolving, owing to the constant ac-

tion of the belt on the rear shaft, the wheel B^4 is slowly revolved, and with it the power-shaft and the notched gear B^5 next it. At this time the lever M^2 , Fig. 16, has reached the depressed portion of the cam, and the tip of the lever M' is in contact with the surface of the notched gear in readiness to enter the notch, as shown in the figure. As the notched gear is slowly revolved with the gear B^4 , the notch B^{5x} is brought under the tip of the lever M' , and said tip is allowed to enter it. At the same moment that part of the gear B^4 which is cut away arrives under the intermediate gear and no further motion of the power-shaft takes place, the intermediate gear being shortly removed by the action of the cam F^3 . This position of the notched gear corresponds to the proper position of the jaws in the revolving head. (Shown in Fig. 1.) Now by the action of the lever and notched gear on the rear-shaft the opening lines of these jaws had already been so adjusted that when the jaws were in the same horizontal plane these lines were properly adjusted for the admission of the funnel, as explained, and hence all is now in readiness for the repetition of the operation described. With the renewed action of the inward-turned projection on the cam F^2 there is a corresponding action of the track 1 by means of the arm L^3 , Fig. 5, which slides the brake 11 backward and liberates the carriage of the holding mechanism preparatory to the bringing of the said carriage back toward the working part of the machine, as described.

I do not wish to be understood as limiting myself to the exact detail of the constructions shown, as many minor departures from said details may be made without departing from the spirit of my invention.

I have thus described one form of my invention; but in some respects I construct my machine often differently from what has been above described. The rear shaft, for instance, need not be made in two entirely separate sections, and, indeed, I most frequently construct the same entire from end to end, as shown in Fig. 17, the constantly-revolving portion forming a sleeve or hollow shaft surrounding the intermittent shaft A , said sleeve bearing the constant pulley P^3 and the gear A^6 and worm A^7 beyond the same, as shown. During the use of the pulley-belt upon the tight pulley on the power-shaft the motion of the same is transmitted through the gear A^5 to the inner rear shaft A , and said shaft revolves backward against the motion of the sleeve on which is mounted the constantly-revolving gear and worm. Again, instead of employing one of the tracks, as described, to slide back and forth for the liberation of the carriage, I more frequently use a third rod 18, running parallel to and back of the tracks, and provided with a collar 19 at the forward end of the same, or near the twisting mechanism, and another collar 20 at the other end of the rod. (See Fig. 2.) The extreme rear end of this rod is attached to the lever L^3 ,

Fig. 5. By impact of the carriage at the end of its journey at either end the clutch G^6 is thrown out of gear with the bevel-wheels that run the driving-wheels, and thus the motion of the carriage is stopped at the end of its course at either end. In case of the use of this rod I employ a stop-lever for the carriage, having a depending peg 21 near its end, adapted to fall over the pin g on the carriage. This peg is rigidly attached to this brake, and as the brake-lever is pivoted as described, when the lever L^3 at the end of the machine acts upon the rod 18 and the collar 20 is thrust backward, there is a pin thereon which projects underneath the brake-lever near its rear end, as shown, Fig. 2. Now, near this rear end of the brake, said brake takes a downward turn, as shown, and as the pin on the collar 20 is thrust backward it acts upon this curve and tends to throw the brake up. This liberates the carriage from the peg 21 at the right moment—that is to say, just when the clutch is thrown into gear with the bevel—which brings the carriage back toward the twisting end of the machine. By this means there is a more positive resistance opposed to the tractile influence of the cord in its twisting and the carriage is sure not to be liberated until the machine is ready.

30 Another variation from the mechanism described, and one which is preferable, although the machine as described will also perform its proper functions, is the securing of the disk A^3 at a later moment than that specified above.

35 Instead of securing this disk immediately after the twisting process is completed, and thus rendering it necessary to go beyond the necessary point of twisting in order to allow for the untwisting accomplished by the stationary

40 gear A^5 , I leave this disk and the shaft upon which it works loose by a proper adjustment of the cam which secures it until after the doubling has been completed. At the same moment that the cam C^2 is operating to secure

45 the disk B^5 a secondary notch in the cam C^3 (shown in dotted lines in Fig. 3) comes into operation, and, being shallow, just allows a small portion of the belt on the rear pulleys to come onto the intermittent pulley, in order

50 to bring the notch in the disk A^3 opposite the point intended to secure it and keep the planes of the holding-jaws horizontal. This occurs, as above specified, just when these jaws are being brought into the same horizontal plane, and

55 the double adjustment brings these jaws into a proper position for the reception of the cord.

Having now described my invention and explained its mode of operation, what I believe to be new therein, and what I therefore claim,

60 is—

1. Holding mechanism and clipping-jaws adapted to be revolved around one another, in combination with removing-jaws adapted to move in front of said jaws, substantially as described.

65 2. Holding mechanism and clipping-jaws adapted to revolve around one another, in

combination with cutting mechanism at one side of said jaws, having a movable member, and means for operating said member, substantially as described. 70

3. Holding mechanism and jaws mounted upon independent axes and adapted to rotate upon said axes and around one another, in combination with removing-arms adapted to move before said jaws, substantially as described. 75

4. Holding mechanism and jaws mounted upon independent axes and adapted to rotate upon said axes and to revolve around one another, in combination with cutting mechanism at one side of said jaws and removing-arms adapted to move before said jaws, substantially as described. 80

5. Holding mechanism and clipping-jaws adapted to revolve around one another, in combination with a feed-funnel adapted to move in front of and between said jaws, substantially as described. 85

6. Holding mechanism and clipping-jaws adapted to rotate around one another, in combination with a feed-funnel adapted to move in front of and between said jaws, and cutting mechanism situated between said jaws and the funnel when in an inoperative position, substantially as described. 90

7. Holding mechanism and tracks whereon said mechanism is adapted to run, in combination with clipping-jaws mounted upon separate axes and adapted to rotate upon said axes and around one another, and a feed-funnel adapted to move in front of and between said jaws, substantially as described. 100

8. Holding mechanism and tracks whereon said mechanism is adapted to run, in combination with clipping-jaws adapted to revolve around one another, a feed-funnel adapted to move in front of and between said jaws, cutting mechanism situated between said jaws and said funnel in an inoperative position, 110 and removing-arms adapted to move in front of said jaws, substantially as described. 105

9. Holding mechanism and tracks whereon said mechanism is adapted to run, in combination with clipping-jaws adapted to revolve around one another, and carrying-wheels bearing an endless cord attached to said holding mechanism, substantially as described. 115

10. Holding mechanism and wheels attached thereto and tracks whereon said mechanism is adapted to run, in combination with clipping-jaws mounted upon separate shafts, adapted to rotate upon said shafts and to revolve around one another, and carrying-wheels bearing an endless cord attached to 125 said mechanism for the purpose of running it upon said tracks, substantially as described.

11. Holding mechanism and tracks whereon said mechanism is adapted to be run, in combination with clipping-jaws adapted to revolve around one another, carrying-wheels bearing an endless cord attached to said holding mechanism, and a funnel adapted to move in front 130

of and between said jaws, substantially as described.

12. Holding mechanism and tracks whereon said mechanism is adapted to run, in combination with clipping-jaws adapted to be revolved around one another, carrying-wheels bearing an endless cord attached to said mechanism, a feed-funnel adapted to move in front of and between said jaws, cutting mechanism arranged between said jaws and the inoperative position of said funnel, and removing-arms adapted to move before said jaws, substantially as described.

13. A holding-carriage having wheels, tracks on which said wheels are adapted to run, a standard mounted upon said carriage, and a hook pivoted upon said standard, in combination with revolving jaws, substantially as described.

14. A holding-carriage having wheels, tracks on which said carriage is adapted to run, a standard mounted upon said carriage, a hook pivoted upon said standard, and a spring for retaining said hook in operative position, in combination with revolving jaws and carrying-wheels bearing an endless cord attached to said carriage, substantially as described.

15. A holding-carriage having wheels, tracks upon which said carriage is adapted to run, one of said tracks bearing a trip, a standard borne upon said carriage, a pivoted hook on said standard and embraced by a scraper, the end of said hook depending into the line of the trip, and a spring for retaining said hook in an operative position, in combination with revolving jaws and carrying-wheels bearing an endless cord attached to said carriage, substantially as described.

16. In a cord-twister, a holding-carriage having wheels, a standard mounted upon said carriage, and a hook pivoted to said standard so as to dip in the vertical plane, in combination with means for dipping said hook in the traverse of the carriage and tracks whereon said wheels are adapted to run, substantially as specified.

17. In a cord-twister, a holding-carriage having wheels, tracks whereon said wheels are adapted to run, one of said tracks being provided with a trip, a standard mounted upon said carriage, a hook pivoted to said carriage and embraced by a scraper, and a spring to retain said hook in an operative position, in combination with carrying-wheels bearing an endless cord attached to said carriage, substantially as specified.

18. Revolving jaws, a guide, and a feed-funnel adapted to slide in said guide in front of said jaws, in combination with a rack attached to said feed-funnel and intermittent gear adapted to be brought into contact with said rack, substantially as described.

19. Revolving jaws, a guide, and a feed-funnel adapted to slide in said guide in front of said jaws, in combination with a rack attached to said feed-funnel, intermittent gear adapted to be brought into contact with said

rack, and a pulley and weighted cord sliding over said pulley and attached to said funnel for the purpose of drawing it in front of said jaws, substantially as described.

20. Revolving jaws, a guideway, a feed-funnel sliding in said guide, a pulley, and a weighted cord running on said pulley and attached to said funnel for the purpose of drawing it in front of said jaws, in combination with a rack pivoted to said funnel and a partly-toothed wheel rotating in the plane of the rack and within the sector through which said rack is adapted to swing on its pivot, substantially as described.

21. Revolving jaws, a guideway, the feed-funnel Q, the pivoted rack Q², the weight and pulley for drawing the funnel forward in front of said jaws, and the wheel D³, in combination with tracks 1 and 2, a holding-carriage running upon said tracks and bearing a hook adapted to be made to intersect the path of said funnel, a pin on said holding-carriage, and a latch for holding said funnel away from said jaws and adapted to pass over said pin on the holding-carriage for the purpose of liberating said latch, substantially as described.

22. Revolving jaws, a guideway, the feed-funnel Q, the pivoted rack Q², the weight and pulley for drawing the funnel forward in front of said jaws, and the wheel D³, mounted upon a shaft D, gearing with the vertical shaft G, in combination with tracks 1 and 2, a holding-carriage running upon said tracks, a pin on said holding-carriage, a latch for holding said funnel away from the jaws and adapted to be liberated by passing over said pin on the holding-carriage, carrying-wheels geared with said vertical shaft, and an endless cord running over said wheels and attached to said holding-carriage for the purpose of drawing said carriage backward and forward, substantially as described.

23. Revolving jaws, a guideway, a funnel adapted to slide in said guideway in front of and between said jaws, a rack attached to said funnel, and intermittent gear adapted to operate said rack, in combination with tracks, a holding-carriage running upon said tracks and bearing a hook adapted to intersect the path of said funnel, and carrying-wheels geared with said intermittent gear and bearing an endless cord attached to said holding-carriage, substantially as described.

24. In a cord-twisting machine, the twisters and a removing-arm swinging in front of the same and at right angles to their direction for the purpose of removing the completed cord, in combination with means, substantially as described, for operating said arm and twisters.

25. In a cord-twisting machine, the twisters and a pair of removing-arms pivoted in the manner described to one another and swinging in front of the same and at right angles to their direction for the purpose of removing the completed cord, in combination with

means, substantially as described, for operating said arm and twisters.

26. In a cord-twisting machine, and in combination with the twister thereof, a fixed 5 moving-arm adapted to swing upward in front of said twister, a downward-swinging arm pivoted thereto, a beak fixed to said pivoted arm, a spring holding said arms apart, and a resisting part in the path of said beak, for the 10 purpose of closing said arms together.

27. In a cord-twisting machine, the twisters and a removing-arm fixed to a pinion and adapted to swing in front of the same, in combination with intermittent gear for operating 15 said pinion so as to accomplish said swinging, as described.

28. In a cord-twisting machine, and in combination with the twister thereof, a fixed removing-arm attached to a pinion and adapted 20 to swing in front of said twister, intermittent gear to operate said fixed arm, a second arm pivoted to the fixed arm and held open by a spring, a beak attached to the pivot of said pivoted arm, and a resisting part in the 25 path of said beak, substantially as described.

29. The twister of a cord-twisting machine, a fixed removing-arm adapted to swing in front thereof and attached to a pinion, a curved spring concentric with said pinion, a second 30 arm pivoted to said fixed arm and held away therefrom by a spring, and a beak attached to the pivot of said second arm, in combination with a constantly-revolving wheel having two series of teeth cut to mesh with said 35 pinion, whereby said arms are revolved, first, into the grasping position, where they hold the completed cord, and, secondly, through an angle subtended by the spring, substantially as described.

40. The clipping-jaw of a twisting-machine, comprising two halves, as B¹³, squared and pivoted together at their rear ends, and a spindle attached to said jaw, and a revolving head provided with a squared perforation, 45 into which said squared ends of said jaws are adapted to be drawn.

31. The clipping-jaws of a twisting-machine, comprising two halves, as B¹³, pivoted together at their rear ends, a revolving head, and a 50 flange, as B⁹, surrounding said jaws, in combination with links pivoted to said jaws and to said flange and spindles to which said jaws are attached, substantially as described.

32. A revolving head having a perforation, 55 in combination with a spindle-case provided with an outside pinion having a rectangular perforation, a spindle extending through said case, jaws pivoted to the end of said spindle and having rectangular portions near their 60 points of pivoting, and gearing for the purpose of meshing with said pinion and driving said spindle, substantially as described.

33. A spindle and jaws pivoted thereto and having a rectangular body, in combination 65 with a pinion having a rectangular perforation fitting the shank of said spindle and an exterior flange, links pivoted to said flange

and to said jaws, and gearing adapted to mesh with said pinion for the purpose of twisting, substantially as described.

34. A spindle-case having a pinion at one 70 end thereof, said pinion being provided with a rectangular perforation, a flange on said pinion, and a spindle extending through said case and pinion and fitting the latter, in combination with a spiral spring attached to said case and to said spindle, jaws pivoted to said spindle at a common point and having rectangular portions near their rear ends, links pivoted to said flange on said pinion and to 80 said jaws, and gearing adapted to mesh with said pinion for the purpose of rotating said jaws, substantially as described.

35. A spindle-case having a rectangular end 85 perforation and a communicating cylindrical perforation, in combination with a spindle projecting therethrough and having jaws pivoted to the end thereof, said jaws having rectangular portions near their bases, a spiral spring attached to said case and to said spindle, a shoe attached to the rear end of said spindle, and a beveled sliding piece adapted to be introduced under said shoe, substantially as described.

36. A spindle-case having a rectangular end 90 perforation and a communicating cylindrical perforation and a flange surrounding the end of said rectangular perforation, in combination with a spindle projecting therethrough and having jaws pivoted to the end thereof, 100 said jaws having rectangular portions near their bases, a spiral spring attached to said case and to said spindle, a shoe attached to the rear end of said spindle, a beveled sliding piece adapted to be slid under the said 105 shoe, and links pivoted to said flange and to said jaws, substantially as described.

37. A revolving head mounted on a shaft and having perforations, spindle-cases extending through said perforations and having 110 themselves perforations squared at one end, and spindles extending through said cases and bearing pairs of jaws pivoted to the ends of said spindles and squared at their bases and shoes at their other ends, in combination 115 with a circular cam loosely mounted on said shaft and having curved slots, through which said spindles extend, and sliding cams bordering said slots and having beveled ends for introduction under said shoes, substantially as 120 described.

38. A revolving head mounted on a shaft and carrying pivoted jaws and attached spindles and spindle-cases extending therethrough, said spindles carrying shoes on their 125 rear ends, in combination with a circular cam loosely mounted on said shaft behind said revolving head, said cam having curved slots, through which said spindles extend, and bordered by sliding cams having bevels for introduction under said shoes, one of said sliding cams being longer than the other, substantially as described.

39. The combination, with the spindles, spin-

dle-cases, and pivoted jaws of a cord-twister and the circular cam having beveled portions for projection beneath the ends of said spindles, adapted to close said jaws, and having 5 notches in its periphery, of the revolving cam C^8 , and wheel and pin D^2 , and the overlying arm K , having the arm K^2 , adapted to be thrust against said notches by the action of said cam and wheel, substantially as described.

40. The combination, with the spindles, spindle-cases, and attached pivoted jaws of a twisting-machine and the circular cam having beveled portions for projection beneath the ends of said spindles for closing said jaws 10 and having notches in its periphery, of a pivoted arm K , having an arm K^2 and a branch K^3 , and the rotating wheel D^2 , bearing a pin adapted to strike the branch K^3 at intervals and thrust the arm K^2 into the notches in the 15 periphery of said circular cam, substantially as described.

41. The combination, with the circular closing-cam of a cord-twister having notches upon its periphery, of the arm K , the spring branch K^2 and the fixed branch K^3 borne thereon, 20 and the revolving wheel D^2 , supporting the pin D^{3x} , which is adapted to strike the fixed branch K^3 at intervals and thrust said spring branch K^2 into said notches, substantially as described.

42. The circular cam of a cord-twister having notches in its periphery, in combination with the wheel D^2 , bearing the pin D^{3x} , the rotating cam C^8 , having two projections thereon, and the arm K , pivoted, as at K' , and provided with the projection K^4 , designed to engage with the projections on the cam C^8 , the fixed arm K^3 , adapted to be brought into the path of the pin D^{3x} , and the pivoted branch K^2 , controlled by the stop K^5 and the spring K^6 , substantially as described.

43. The closing-cam of a cord-twister, in combination with a beveled brake provided with a beak and loosely mounted on a shaft 45 on which said cam is mounted, a friction-wheel on a separate shaft and set in the path of said beak, and means for pushing said brake against said closing-cam, substantially as described.

44. The closing-cam of a cord-twister, provided with a cylindrical flange, in combination with a beveled brake provided with a beak and fitting over said flange, a friction-wheel set in the path of the beveled brake, 55 and means for pushing said brake against said closing-cam, substantially as described.

45. The closing-cam of a cord-twister, having a cylindrical flange, in combination with a beveled brake fitting over said flange and 60 adapted to be applied thereto, the lever S^2 , mounted on the vertical rotatable shaft S , a spring for actuating said brake, lever S^3 , and the cam C^6 , against which said lever is adapted to rest normally, substantially as described.

46. In a cord-twister, a closing-cam, a beveled brake mounted loosely upon a shaft and

provided with a beak S^7 , a pin S^5 , and a spring S^4 , secured to a stop S^6 and abutting upon a vertically-immovable part of the machine, in combination with a friction-wheel mounted 70 upon a separate shaft and in the line of the beak, the vertical rod S , bearing the levers S^2 and S^3 and an attached spring S' , the former being bifurcated and embracing a portion of said beveled brake, and the cam C^6 , against 75 which the lever S^8 rests, and by which said beveled brake is operated, substantially as described.

47. In a cord-twister, pivoted clipping-jaws having squared ends near their pivotal point, 80 in combination with pinions having square perforations, into which said jaws are adapted to be fitted, outside and inside gear surrounding said pinions and the inside teeth of which mesh with said pinions, and driving mechanism gearing with the outside teeth of said outside and inside gear, substantially as described.

48. In a cord-twister, two clipping-jaws operatively embraced by pinions when closed, 90 and the opening planes of which may be brought into a common plane, an outside and inside gear surrounding said jaws, the inside teeth of the same meshing with those of said pinions, in combination with a driving-shaft 95 operatively connected with said outside and inside gear, said shaft having a notched wheel, and a lever provided with a projection adapted to fit into said notch when said jaws have their opening planes in a common plane, substantially as described.

49. In a cord-twister, two clipping-jaws operatively embraced by pinions when closed, 100 and the opening planes of which may be brought into a common plane, an outside and inside gear surrounding said jaws, the inside teeth of the same meshing with those of the pinions, in combination with a driving-shaft 105 operatively connected with said outside and inside gear by means of a spur-wheel A^5 , gearing with the outer teeth of said outside and inside gear, a notched wheel on said driving-shaft, a cam C^5 , and a pivoted lever C^{5x} , resting upon and operated by said cam C^5 and provided with a projection adapted to enter 115 the notch on said notched wheel when the opening planes of the jaws are in the common plane, substantially as described.

50. A shaft bearing a revolving head having perforations, jaw-carrying spindles held in said perforations and provided with pinions, outside and inside gear surrounding said pinions, the inner teeth of the same operating said pinions, and a driving-shaft bearing a spur-wheel gearing with the outer teeth of 120 said outside and inside gear, in combination with a cam-shaft bearing the cams C^4 and C^5 , a fast and a loose pulley on said shaft carrying the revolving head, a notched wheel borne on said driving-shaft, a shifter operated by 125 said cam C^4 to throw the power-belt back and forth on said fast and loose pulleys, and a le- 130

ver operated by said cam C⁵ to enter the notch in said notched wheel, substantially as and for the purposes specified.

51. In a cord-twister, a power-shaft for doubling, having a notched gear-wheel fixed thereto, and a gear B⁴, also fixed thereto, a cam-shaft bearing a cam C² and a gear C', a lever having a projection fitting into said notch on said notched gear and controlled by said cam C², a secondary cam-shaft bearing a cam F³ and geared with said gear C' by the gear H⁵, and the rear shaft driving said secondary cam-shaft and bearing the gear A⁶, in combination with intermediate gear transmitting power from said gear A⁶ to said gear B⁴ and provided with a lever T', resting on and controlled by the cam F³, substantially as described.

52. A power-shaft for doubling, a notched gear B⁵, mounted upon said shaft, a cam-shaft bearing a cam C², and gear connecting said shafts, in combination with a bell-crank lever composed of the two arms M' and M², the latter arm resting upon said cam and the former provided with a projection fitting into the notch in said notched gear, and a spring M⁴, acting to keep said arms in position, substantially as described.

53. In a cord-twister, the transmitting-shaft, the vertical shaft driven by said transmitting-shaft, gears g² g⁵ g⁶, for driving the carrying mechanism, and a secondary cam-shaft driven by said transmitting-shaft and bearing the cam F², in combination with the rod L, provided with the controlling-lever L', actuated by said cam F² and the throwing-lever L², and a reversing-clutch G², attached to said reversing-lever, substantially as described.

54. In a cord-twister, the carrying mechanism and driving mechanism and oppositely-rotating loosely-mounted bevel-wheels on the shaft of the driver of said carrying mechanism, said bevel-wheels being provided with inner clutch-teeth, in combination with the cam F², driven by the driving mechanism, the rod L, directed by means of the lever L², actuated by said cam, and bearing a lever L² at its lower end, and a sliding clutch upon said shaft of the carrying-driver, attached to the end of said lever L², and provided with teeth adapted to mesh with said inner clutch-teeth on said bevels, substantially as described.

55. In a cord-twisting machine, the twister, the feed mechanism, and the rigid knife U², in combination with the cam C⁹ and the pivoted knife playing against said rigid knife and having its rear end constantly abutting against said cam, substantially as described.

56. In a cord-twisting machine, the twister, the feed mechanism, and the rigid knife U², in combination with the cam C⁹, the pivoted knife playing against said rigid knife and having its rear end constantly abutting against said cam, and the spring U⁴, acting to produce this constant abutting of the rear end against the cam, substantially as described.

57. In a cord-twisting machine, the twisting-shaft and the constant driving-shaft having abutting pulleys, in combination with a driving-belt, a shifter for said belt, and a clutch actuated by said shifter to unite said pulleys when the belt is on the twisting-shaft, substantially as described.

58. In a cord-twisting machine, the twisting-shaft and the constant driving-shaft having abutting pulleys, in combination with a driving-belt driving said pulley, a toothed clutch on said constant shaft and fast thereto, a sliding toothed clutch on said twisting-shaft, and a shifter for said belt serving to bring said clutches together, substantially as described.

59. In a cord-twisting machine, the twisting-shaft and the constant driving-shaft having abutting pulleys, in combination with a driving-belt, a toothed clutch fast to said constant shaft, a feathered sliding toothed clutch on end of said twisting-shaft, a loose disk surrounding said constant shaft and connected with said feathered clutch by the pins P', and a shifter for said belt serving to bring said clutches together, substantially as described.

60. In a cord-twisting machine, the twisting-shaft, the constant driving-shaft, abutting pulleys on said shafts, a belt running said pulleys, and a shifter for throwing said belt, in combination with a pin on said shifter, a bell-crank having one arm in the path of said pin, a sliding toothed clutch on said twisting-shaft, a fixed toothed clutch on the end of said constant shaft, and a loose disk surrounding said constant shaft and attached to said sliding clutch by means of the pins P', extending back to the other end of said bell-crank, substantially as described.

61. In a cord-twisting machine, a twisting-shaft, a constant driving-shaft, a belt, and pulleys mounted on said shafts and abutting against one another, in combination with a sliding clutch on said twisting-shaft, a fixed clutch on the end of said constant shaft, adapted to be brought into contact with said sliding clutch, both of said clutches bearing teeth so beveled, as described, that the teeth on said sliding clutch act to drive the other clutch and that the teeth on said fixed clutch tend to throw said clutches apart, and means for shifting said belt and clutch, substantially as described.

62. The guides 13 and the feed-carriage sliding in said guides and having a rack pivoted thereto, in combination with the gear-wheel D³, adapted to mesh with the teeth of said rack when they are in the horizontal plane, and the pin R³, projecting through the bottom of said guide and abutting against the under side of said rack, substantially as described.

63. In a cord-twister, in combination with the feed-carriage, the pivoted rack thereon, a gear D³, a lever R, bearing the pins R³ and R', and the cam C⁸, against which said pin R' abuts, and whereby said pin R³ is raised, substantially as described.

64. In a cord-twister, a feed-carriage having a pivoted rack thereon, means for lifting said rack, a broken gear meshing with said rack when in the horizontal plane, guides in which said carriage is adapted to slide, and such a number of teeth on the surface of said broken gear as to bring the said carriage back into an inoperative position, substantially as described.
65. In combination with the reversing-gear of a cord-twister, a rod 18, connected therewith, bearing collars 19 and 20, the latter collar being provided with a side projecting pin, tracks, a carriage running upon the same and bearing a pin *g*, said carriage being connected with the reversing-gear, and a pivoted brake-lever attached to one of said tracks next the said rod and having a cam-curve therein adapted to come in contact with said pin on the collar 20, substantially as described.
66. In a cord-twister, a rear shaft bearing an intermittent and a constant pulley having a belt running over them and a notched disk thereon, in combination with belt-shifting mechanism, a cam *C*³, having a primary and a secondary notch for actuating said mechanism, and a cam and transmitting mechanism for securing said notched disk, as described, said secondary notch acting, as described, to project a portion of the belt onto the intermittent pulley at the moment of the action of the securing mechanism, substantially as described.
67. The twisting-jaws, a shaft, and means for rotating said jaws for twisting, a second shaft, and means for revolving said jaws about a common center for doubling, and a hollow shaft surrounding said first-named shaft and bearing a worm, in combination with a cam-shaft, means whereby said cam-shaft regulates the twisting and doubling mechanisms, and means connected with said worm whereby said cam-shaft is actuated, substantially as specified.
68. In a cord-twister having twisting-jaws, a rear shaft for the actuation of said jaws for twisting, a cam-shaft bearing a cam *C*³, a belt-shifter *O*, actuated by said cam, a pulley upon said shaft, and a belt running over the same, in combination with a sleeve surrounding said shaft, a pulley borne upon said sleeve, a worm upon said sleeve for actuating said cam-shaft, a clutch upon the end of said sleeve, a clutch loosely surrounding said shaft and adapted to be brought into engagement with said clutch upon said sleeve, and an arm actuated by said shifter to throw said clutches into engagement with one another, substantially as described.

In testimony whereof I affix my signature in presence of two witnesses.

JOHN L. INMAN.
